US0D1103246S

(12) **United States Design Patent** (10) **Patent No.:** **US D1,103,246 S**
(45) **Date of Patent:** **** Nov. 25, 2025**

(54) **CAMERA**

(71) **Applicant:** **Anhui Sharetronic Data Technology Co., Ltd**, Hefei (CN)

(72) **Inventors:** **Sihua Geng**, Hefei (CN); **Zhou Yi**, Hefei (CN); **Jianfei Liu**, Hefei (CN)

(73) **Assignee:** **Anhui Sharetronic Data Technology Co., Ltd**, Hefei (CN)

(**) **Term:** **15 Years**

(21) **Appl. No.:** **29/943,357**

(22) **Filed:** **May 21, 2024**

(30) **Foreign Application Priority Data**

May 11, 2024 (CN) 202430277208.2

(51) **LOC (15) Cl.** **16-01**

CLAIM

The ornamental design for a camera, as shown and described.

DESCRIPTION

FIG. 1 is a perspective view of our new design, showing a camera;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The line shading in FIGS. 1-8 represents contour and not surface ornamentation.

(Continued)

The broken lines shown in the figures illustrate environmental or other features that form no part of the claimed design.

1 Claim, 8 Drawing Sheets
